DESIGN FOR A CUTLERY HOLDER OR SIMILAR ARTICLE

Arthur P. Miller, New Kensington, Pa.

Application December 24, 1942, Serial No. 109,125

Term of patent 14 years

To all whom it may concern:

Be it known that I, Arthur P. Miller, a citizen of the United States, residing at New Kensington, in the county of Westmoreland and State of Pennsylvania, have invented a new, original, and ornamental Design for a Cutlery Holder or Similar Article, of which the following is a specification, reference being had to the accompanying drawing, forming a part thereof, in which:

Fig. 1 is a perspective view of the cutlery holder or similar article, showing my design;

Fig. 2 is a sectional view taken on the line II—II of Fig. 1; and

Fig. 3 is an elevational view thereof.

I claim:

The ornamental design for a cutlery holder or similar article, substantially as shown.

ARTHUR P. MILLER.
